UNITED STATES PATENT OFFICE.

JULIAN RANKIN, OF LOUISA, KENTUCKY.

DESIGN FOR A VEHICLE RADIATOR ORNAMENT.

Application filed May 2, 1925. Serial No. 13,304. Term of patent 7 years.

To all whom it may concern:

Be it known that I, JULIAN RANKIN, a citizen of Germany, residing at Louisa, in the county of Lawrence and State of Kentucky, have invented a new, original, and ornamental Design for Vehicle Radiator Ornaments, of which the following is a specification, reference being had to the accompanying drawing, forming a part thereof.

Figure 1 is a front elevational view of a

vehicle radiator ornament, showing my new design.

Figure 2 is an edge elevational view of a vehicle radiator ornament showing my new design.

I claim:

The ornamental design for a vehicle radiator ornament, as shown.

JULIAN RANKIN.
